UNITED STATES PATENT OFFICE.

FRANK W. TRABOLD AND JOHN T. KNOX, OF NEW YORK, N. Y.

DENTAL TOOL.

1,158,872.

Specification of Letters Patent.

Patented Nov. 2, 1915.

Application filed December 17, 1914. Serial No. 877,717.

To all whom it may concern:

Be it known that we, FRANK W. TRABOLD and JOHN T. KNOX, citizens of the United States of America, residing in the borough of Brooklyn, county of Kings, city and State of New York, have invented certain new and useful Improvements in Dental Tools, of which the following is a specification.

10 The invention is particularly directed to a dental tool for removing the dowel pins (called posts) used in attaching crowns to roots. When a crown has become broken or has been removed for any other reason, the 15 post by which it was connected to the root (usually by cement or the like) is often difficult to extract from the root, and various tools have been proposed for this purpose.

The present invention relates to an improved device of this character which can be easily operated by one hand, and in which the removal of the post is accomplished without pain to the patient.

The invention in its preferred form comprises a pair of forceps adapted to engage the protruding end of the post, means for holding the forceps tightly gripping the post, and compensating means for exerting a balanced thrust against the top of the 25 root whereby to pull out the post. The operator closes the forcep jaws upon the post and locks or clamps them together, and then by closing a lever arm or handle exerts a 30 thrust through the compensating means against the top of the root which pulls out 35 the post.

In the drawings, Figures 1 and 2 are respectively side and edge views of the tool in its preferred form; Fig. 3 is a fragmentary 40 side view partly in section showing the extracting operation; Fig. 4 is a similar view showing the tool at the end of the extracting operation; Fig. 5 is an edge view in mid-section showing the parts in the same position as Fig. 4; Fig. 6 is a view corresponding to Fig. 1 showing a modified construction; Fig. 7 is a sectional view showing the construction of Fig. 6.

Referring to the drawings, A and B are 50 the handles of a pair of forceps pivoted on a pin C and having jaws *a b* adapted to grip the protruding portion of the post. When the forceps are closed together to grip the post, it is necessary to have some means 55 for holding them so closed, and for this purpose we provide preferably a sliding band

D which can be slipped along a portion *c d* of the handles where they are slightly out of parallel, so that as it is slipped away from the pivotal point it acts to draw the jaws together by an application of the wedge principle.

In order to make the extracting operation as nearly painless as possible, it is customary in tools of this class to exert the reacting thrust against the end of the root, and for this purpose it is customary to apply one or two thrust pins to bear upon the root. These pins in the improved tool are lettered E E, being preferably directed as close together as practicable at their bearing ends, while their main or body portions are shown as formed as round pins *e e* which slide through some suitable guide and are connected at their opposite ends to a thrust lever F which is pivoted at *f* to one of the jaws, and is shaped so that its long arm serves as a handle adapted to fold against one of the forcep arms A or B, while its short arm projects into the space between the forcep arms and is connected to the pins. For guiding the pins, they are conveniently passed through the projecting ends of the pintle C as shown.

It is an important feature of this invention that the reacting thrust during the extracting operation is balanced or compensated, so that in the case of any inequality of level of the top of the root, the thrust against the root shall be uniform and without exerting any tilting tendency. For this purpose the connection between the thrust pin and the extracting lever is accomplished through an equalizing lever or rock piece G, best shown in Fig. 5, which is connected at 95 its ends to the thrust pins and at its middle to the lever F, the latter connection being best made through a stirrup H which is pivoted to the short arm of the lever F by one pin, and to the middle of the equalizer 100 G by another pin at right angles thereto. This construction permits either pin to project beyond its mate, and results in the advantage that as the extracting force is applied the reaction is divided equally between 105 the two pins irrespective of whether the surface of the root be true or otherwise. For example in Fig. 5 the root is shown with an exaggerated inequality on its face to which the pins adapt themselves by the rocking of the equalizing lever G.

The tool is preferably applied so that the

plane of the jaws *a b* is at right angles to the direction of the row of teeth. Hence to enable the tool to be introduced into the space between the teeth, it is desirable as before stated to bring the bearing ends of the pins *E E* as close together as will admit the post and the working ends of the jaws between them, in order that the tool may be introduced within the width of the narrowest tooth.

The details of construction of the tool may be considerably varied without departing from the invention. For example Figs. 6 and 7 show a modified construction illustrating certain practicable variations. In this case the jaws *a b* are made somewhat longer, the push pins *E E* are made shorter and nearly straight and are guided in a projection *g* from the jaw *b*, and the lever *F* is pivoted to this same jaw, the parts *G* and *H* being located above the pintle *C'* instead of beneath it. For clamping the forceps close, a toothed sector *J* is shown in place of the slide *D* first described, this sector being pivoted to one jaw and having teeth engaging a projection on the other. These figures also show a different arrangement of the handles *A B* and lever *F*, which instead of being extended symmetrically with the center line of the jaws, are extended approximately at right angles thereto, so as to make the tool applicable in the case of molars, the tool first described being designed only for use with front teeth (the use of crowns supported upon dowel posts being mainly limited to front teeth).

While we have shown and described several forms of the invention, it will be understood that we do not wish to be limited thereto, since various changes may be made therein without departing from the spirit of the invention.

We claim as our invention:—

1. A pair of forceps having a pair of push

pins, means for exerting a thrust against the push pins, and equalizing means for distributing the thrust to such push pins.

2. A pair of forceps having a pair of push pins, means for exerting a thrust against the push pins, and an equalizing lever for distributing such thrust to the push pins.

3. A pair of forceps having push pins, and a thrust lever pivoted to the forceps and having an equalizing engagement with the push pins.

4. A pair of forceps having a pair of push pins arranged close against opposite sides of their jaws, and a thrust lever pivoted to the forceps, connected to said push pins, and movable against the forceps handles to exert a thrust to protrude the push pins.

5. A pair of forceps having push pins, a thrust lever pivoted to the forceps, and an equalizing lever receiving the push of such thrust lever at its fulcrum, and transmitting such thrust from its arms to the push pins.

6. A pair of forceps having a pintle pin projecting at opposite ends, a pair of push pins moving through holes in the projecting portions of said pintle, an equalizing lever pivoted to the ends of said push pins, and a thrust lever engaging the middle of said equalizing lever.

7. In a post puller, the combination of means adapted to grip the post, and a thrust device adapted to bear against the tooth at a plurality of points, the post puller having equalizing means adapted to distribute the thrust between such points.

In witness whereof, we have hereunto signed our names in the presence of two subscribing witnesses.

FRANK W. TRABOLD.
JOHN T. KNOX.
